UNITED STATES PATENT OFFICE.

GROVER H. DECKER AND HOMER A. DECKER, OF TOLEDO, OHIO.

INTERNAL-COMBUSTION MOTOR.

Application filed November 7, 1927. Serial No. 231,476.

This invention relates to an internal combustion motor which has been designed with the object of eliminating the knocks resulting from the explosion of the fuel, particularly in motors of the high compression type. It consists primarily in so constructing the motor head that the fuel charge does not explode in direct contact with the end of the piston, but the expansive effect of the exploded gases is directed against the end of the piston immediately after the explosion. Regardless of the amount of compression, and the rate at which the fuel is burned, the resulting gases will be fed through a port or ports into contact with the head of the piston, and although the application of the expansive force against the head of the piston will be as nearly instantaneous as practicable, there will be a sufficient regulation of the flow through the ports to prevent the sharp impact which causes a knock.

The essential features of construction which insure the beneficial result above outlined, will be more fully explained in connection with the accompanying drawings which illustrate the same in detail.

In the drawings:

Figure 1 is a vertical section taken centrally through the upper part of one of the cylinders of the motor.

Fig. 2 is a section taken on the line 2—2 of Fig. 1.

Fig. 3 is a view similar to Fig. 1 but on a reduced scale, showing a modified form of the invention.

In the form of the invention shown in Fig. 1, the numeral 5 indicates one of the cylinders of an internal combustion motor having a removable head 6. Adjacent the upper end of the cylinder there is provided a combustion chamber 7 having suitable inlet and outlet ports, one of which is indicated at 8 and provided with a valve 9. A piston 10 is reciprocable within the cylinder 5 and is provided with a connecting rod 11 of the usual type. The parts are so proportioned, however, that the piston 10, when in its uppermost position, extends somewhat above the end of the cylinder 5 or above the ports.

A shield or cap 12 is integrally connected to the inside of the cylinder top or head 6 by suitable webs 13. This shield or cap has a depending peripheral lip 14 forming a pocket which receives the upper end of the piston 10 at the upper limit of its stroke. Ports 15,

preferably larger than the intake valve, connect the combustion chamber 7 with the upper part of the cylinder 5 beneath the shield or cap 12 so that the exploded gases are admitted into contact with the end of the piston 10 immediately after it starts upon its return stroke.

The upper end of the piston 10 is shown as convex and the inner face of the cap 12 is correspondingly shaped. This specific shape, however, is not essential. It may be desirable to provide a space 16 within the cap 12 and connect the same with the water cooling system of the motor. The spark plug 17 is preferably located substantially at the center of the chamber 7.

In the modified construction shown in Fig. 3, the head 6^a is formed with a pocket 12^a for receiving the end of the piston 10^a. The combustion chamber 7^a is, in this case, located wholly at one side of the cylinder and communicates therewith through a single port 15^a formed between the upper end of the cylinder and a lip 14^a which depends from the head 6^a.

In the operation of the invention the piston, on its compression stroke, compresses the fuel charge in the combustion chamber. Slightly before the completion of the up stroke the ports leading into the cylinder are closed and at about this time the fuel charge is ignited. In motors of the high compression type, the explosion takes place very suddenly and the impact of the same usually causes an unavoidable knock, as if a sharp blow were struck against the end of the piston. By reason of the present construction, however, the end of the piston is protected against this impact, but just as soon as it starts upon its return stroke the exploded gases flow through the ports into contact with the end of the piston in a smooth and even manner, taking advantage of a high compression without the usual roughness. By making the pocket of the proper depth, the proper timing of the above conditions can be secured. The spark should be timed to take place at or about the time that the ports are covered by the piston upon its compression stroke.

It is also to be noted that as the piston approaches the end of its compression stroke, the fuel mixture which is at that time in the upper part of the cylinder, is forcibly expelled in a comparatively thin sheet through the port or ports with great turbulence, with the re-

sult that the entire fuel charge is thoroughly mixed and atomized and complete combustion is effected.

It will be apparent that the invention is 5 adapted to be applied to any of the various types of internal combustion motors. It is also apparent that the shape and arrangement of the various parts of the invention may be modified to a considerable extent without any 10 material departure from the essential features as defined in the claims.

What we claim is:

1. In an internal combustion motor, the combination with a cylinder and a piston reciprocable therein, of a combustion chamber near the end of the cylinder, and a cap connected with the cylinder and covering the head of the piston at the limit of its compression stroke and provided with means for admitting the exploded gas from the combustion chamber thereto as the piston starts on its return stroke.

2. In an internal combustion motor, the combination with a cylinder and a piston reciprocable therein, of a combustion chamber near the end of the cylinder, and means for shielding the entire end of the piston equally from the impact of the exploded gas at the instant of the explosion, but admitting the 30 exploded gas thereto as the piston starts on its return stroke.

3. In an internal combustion motor, the combination with a cylinder and a piston reciprocable therein, of a combustion chamber near the end of the cylinder and having ports leading to opposite sides of the cylinder near the end thereof, so that they are covered by the piston at the limit of its compression stroke, and a cap adapted to receive the head 40 of the piston, said ports serving to admit the exploded gas to the cap as the piston starts on its return stroke.

4. In an internal combustion motor, the combination with a cylinder and a piston reciprocable therein, of a combustion chamber adjacent the end of the cylinder and extending beyond opposite sides thereof, and a shield between said chamber and the piston and covering the head of said piston at the 50 limit of its compression stroke, said chamber having ports leading directly to opposite

sides of the cylinder beneath said shield, said ports being in position to be uncovered by the piston as it starts upon its return stroke.

5. In an internal combustion motor, the combination with a cylinder, of a head for said cylinder having a combustion chamber therein, a piston reciprocable in said cylinder and having a rounded end, a cap within said chamber covering the end of said piston 60 at the limit of its compression stroke, said cap being dished to conform to the surface of the piston head, and means for admitting the exploded gas between the cap and piston as the piston starts on its return stroke. 65

6. In an internal combustion motor, the combination with a cylinder, of a head for said cylinder having a combustion chamber therein extending over the end of the cylinder with a spark plug located near the center 70 thereof, a piston reciprocable in said cylinder, a cap forming a part of said head and covering the head of said piston at the limit of its compression stroke, and means for admitting the exploded gas between the cap and piston 75 as the piston starts on its return stroke.

7. In an internal combustion motor, the combination with a cylinder, of a head for said cylinder having a combustion chamber therein extending over the end of the cylinder, with a spark plug located near the center thereof, a piston reciprocable in said cylinder, and a cap forming a part of said cylinder head and covering the head of the piston at the limit of the compression stroke, said 80 chamber having ports leading directly to opposite sides of the cylinder beneath said cap, said ports being in position to be uncovered by the piston as it starts upon its return stroke. 85

8. In an internal combustion motor, the combination of a cylinder, a piston reciprocable therein, a combustion chamber, means for exploding the fuel charge in said chamber, and means controlled by the movement 90 of the piston for determining the time at which the force of the exploded fuel charge becomes effective.

In testimony whereof, we have hereunto signed our names to this specification.

GROVER H. DECKER.
HOMER A. DECKER.
